UNITED STATES PATENT OFFICE.

JACOB ATLAS, OF VISTA GRANDE, CALIFORNIA.

INTERCHANGEABLE WINDOW-WEIGHT.

1,077,924.

Specification of Letters Patent.

Patented Nov. 4, 1913.

Application filed September 5, 1912. Serial No. 718,662.

To all whom it may concern:

Be it known that I, JACOB ATLAS, a citizen of the United States, residing at Vista Grande, in the county of San Mateo and State of California, have invented a new and useful Interchangeable Window-Weight, of which the following is a specification in such full and clear terms as will enable those skilled in the art to construct and use the same.

This invention relates to an interchangeable window weight and its object is to provide means whereby the expense of making such weights may be greatly reduced as well as to provide means whereby a better weight may be produced.

It will be understood by those skilled in the art that the ordinary cast iron window weights are very brittle and that the cast iron is so shaped that there must be a considerable number of different sizes of weights to accommodate them to all sizes of windows. Moreover, whenever a weight is broken it is of no value since it seldom is then of the proper weight to be used to balance the window.

With the present invention it is contemplated that but a limited number of different sizes of weights shall be made, smaller weights being made by omitting some and larger weights being made by adding such a number of smaller pieces as may be demanded to make up a weight to balance a given sash.

In the drawings in which the same numeral of reference is applied to the same portion throughout the several views, Figure 1 is a side elevation of a completed weight having four sections, Fig. 2 is a vertical sectional view of the weight illustrated in Fig. 1, Fig. 3 is a side elevation of the top casting, Fig. 4 is a side elevation of the bottom casting used, Fig. 5 is a side elevation of one of the intermediate weight portions, Fig. 6 is a plan view of the weight shown in Fig. 1, and Fig. 7 is a horizontal sectional view of the weight illustrated in Fig. 1.

It is contemplated that the weight shall have a bottom piece 1 which is threaded as indicated at 2 and which has a groove at the edges as indicated at 3, so that it can be placed within a sheet metal receptacle 4, the lower edges of said receptacle being bent

to fit into the grooves 3 at the edges of the bottom piece 1. This bottom piece will be 55 dropped into the receptacle 4 from the top and thereafter a tube 5 is placed against the bottom piece 1 and the receptacle 4 is then filled with a suitable plastic material as cement and sand, which plastic material is 60 then allowed to harden.

At the upper end the receptacle 4 fits into a receptacle 6 which receptacle has a flat bottom 7 and depending flanges 8 with an overhanging shoulder 9 to prevent the passing weights from tearing out the edges of the receptacle 4. The receptacle 6 is of a different length from the receptacle 4, but it is likewise filled with a cementitious material 10 and it has a tube 11 extending there- 70 through.

Above the receptacle 6 there is a receptacle 12 in every respect the same as the receptacle 6, save that it is of a different length from the receptacles 4 and 6. Above 75 the receptacle 12 there is a receptacle 13 which has a flat bottom 14 and flanges 15 and which fit the top of the receptacle 12. This receptacle 13 has a pyramidal top 16 which fits into the top of the receptacle 13, 80 while at the same time it is smooth at the edges to prevent it from interfering with other weights against which it may swing.

The receptacle 13 has a tube 17 extending from the bottom 14 into the tube 16, said 85 tube being held in place by means of a body of plastic material 18 which fills the lower portion of said receptacle. The object of leaving the receptacle 13 partly empty is to provide means whereby the weights may be 90 increased to exactly balance a given sash, that is, a number of pieces as for example 4, 6, 12 and 13 may all be assembled together by means of the eye-bolt 19 which passes through the several tubes in each section, 95 but it may be found that such a weight does not quite balance the sash, in which event the receptacle may be filled with sand or any suitable material until the weights used exactly balance the given sash.

The exterior of the several weight members may be made of any suitable sheet metal or other sheet material suitably seamed over as illustrated at 20 and the cross section may be either a rectangle, or a circle or any other 105 form.

Having thus described my invention what I claim as new and desire to secure by Letters Patent of the United States, is as follows:

5. An interchangeable window weight comprising a plurality of weighted receptacles, one nested into the next adjacent receptacle, said weight having a pyramidal top and bottom, and a bolt extending through the sev-

eral receptacles and secured in the bottom 10 receptacle, substantially as described.

In testimony whereof I have hereunto set my hand this 26th day of August A.D. 1912, in the presence of two subscribed witnesses.

JACOB ATLAS.
